E. S. HALSEY

FLOODED HORIZONTAL REFRIGERATING COIL

Filed April 25, 1925

Inventor

Edward S. Halsey
by Arthur M. Reed, atty.

UNITED STATES PATENT OFFICE.

EDWARD S. HALSEY, OF WASHINGTON, DISTRICT OF COLUMBIA, ASSIGNOR OF ONE-
THIRD TO ROYCE A. RUESS, OF WASHINGTON, DISTRICT OF COLUMBIA.

FLOODED HORIZONTAL REFRIGERATING COIL.

Application filed April 25, 1925. Serial No. 25,827.

To all whom it may concern:

Be it known that I, EDWARD S. HALSEY, a citizen of the United States, residing at Washington, in the District of Columbia, 5 have invented certain new and useful Improvements in Flooded Horizontal Refrigerating Coils, of which the following is a specification.

The nature of my invention is an elongated horizontally disposed refrigerating coil unit constituted by a compact, continuous series of pipe convolutions preferably in the form of a spirally wound helix, the ends of which pipe connect with a common 10 float chamber, one of said pipe ends entering below the float controlled refrigerant liquid level and the other end connecting at a higher point, preferably above the liquid level, so that the liquid can enter the lower 15 end of pipe by gravity within the lower branch of the pipe and adjacent to the liquid entrance is provided a sensitive floating check valve, so that as soon as ebullition is established by the starting up of a connected 20 compressor-condenser unit (not shown) the agitation from the expansion and intermittent recessions of the gas pressure in the lower branch of the pipe will chatter the valve intermittently, seating it and forcing 25 the gas and liquid through the successive convolutions of the pipe coil and thence back into the upper portion of the float chamber by an intermittent pumping action.

Formerly it has not been found feasible 30 to operate long pipe coils formed in a series of lateral convolutions from a flooded chamber of constant level on account of the air or gas-trapping action of each convolution, especially so when the top end of any one of 35 all convolutions extend above the liquid level maintained by the float. For this reason in commercial applications of the flood system it has been necessary to form the refrigerating loops below the liquid level 40 and lead frequent gas vents from them up to the float chamber. In spite of this disadvantage, the flood system has certain decided advantages over that of the expansion valve system of continuous low pressure, such as the utilization of a low-pressure control, higher average efficiency, and more rapid depression of temperature. The objects of the present invention are 45 to provide an efficient and symmetrical long and slender horizontal refrigerating coil on

the flood system to supply an urgent need for various commercial installations in which no present known form of cooling unit is well adapted or possible of application, such as glass display counters now 50 iced from long, slender ice troughs across the full length at the back of glass display counters. Further, the invention contemplates a unit which can be suspended close to the top and extend the full length of the 55 counter and which may be provided with a drain trough attached so as to make an attractive display without interference with the food display space beneath it.

Further objects are the provision of long 60 units adaptable to market boxes in which an overhead ice bunker extends the entire length of the box and into which one or more of the coils can be suspended across the top or to one side, leaving adequate 65 space for the storage of food or ice.

Still further objects are, economical construction and the convenience of designing 70 flat wall coils or frosted coil pipe words for window display.

In the drawings:

Figure 1 is a side elevation partly in section of my preferred form of refrigerating coil unit.

Fig. 2 is an enlarged detail view of the 75 inlet end of the pipe in which the check valve is located.

Fig. 3 is a section on line 3—3, of Figure 80 1, and

Fig. 4 is a side elevation of a modification 85 of my invention in which the pipe coil is laid in a flat plane.

Referring in detail to the drawing, C represents a cylindrical float chamber having a conventional float-controlled valve V 90 operated by the lever float F. This float valve is fed from the compressor through the liquid line indicated and the gas from this chamber is exhausted by a compressor (not shown) connected to the gas outlet pipe 95 designated on the drawing. This portion of the apparatus is now employed by the commercial machine known as Frigidaire. In carrying out my improvements, I employ for my preferred construction the helically 100 coiled pipe 1, the lower branch end of which returns within the convolutions of the coils to the float chamber below the liquid level determined by the float as indicated at 105 2. The other end 3 of this coil enters the float 110

chamber preferably at the top thereof. By this arrangement the liquid is free to fill the horizontal arm of the coil by gravity and the first coil up to the natural level of the liquid. Close to its entrance to the float chamber this pipe is provided with a check ball 5 and conical seat 4 with a stop pin 6. The ball is preferably made of resilient material which will nearly float in the refrigerant liquid, so that it is very easily seated or unseated. The valve seat may be formed by a union joint between the seat and pin to provide convenient inspection or replacement of the ball. The helical coil is made rigid and secured to the float chamber by means of three spaced rods 8 soldered respectively to each convolution of the coil. Soldered to the lower horizontal branch of the coil is a heat-absorbing fin 7 of sheet copper soldered to the coil by a series of lugs 9. The function of this heat-absorbing fin is to concentrate the transmission of heat to the lower liquid filled branch of the coil at its points of juncture therewith, thereby concentrating and accelerating ebullition at these points. The metal drip trough 10, desirable if the coil is suspended directly over produce on display and being attached by copper straps making intimate thermal contact to the coil, it also acts as a heat absorbing surface to augment or substitute the effect of that of fin 7 just described. From this construction it is obvious that at each spasmodic expansion of gas in this lower branch the check will be closed and a portion of its liquid contents will be discharged with gas into one of the succeeding convolutions and upon a recession of each gas convulsion the ball will be unseated, allowing a new portion of liquid to pass the check valve, thus establishing a repeating intermittent pumping action and consequent circulation throughout the coil, thereby discharging any air or gas that may accumulate in the upper portion of the pipe convolutions into the float chamber, from whence they are withdrawn by the compressor in a continuous cycle.

The modification shown by Figure 4 is introduced to indicate that the coils may be made up into various shapes, such as word writing or flat coils, as may be desired.

Also the coils may be wound of larger diameter than the float chamber and the float chamber be enveloped by the convolutions of the coil, and is obviously subject to many other modifications.

What I claim is:

1. An evaporator comprising a refrigerating float chamber; means for maintaining a constant refrigerant level in such chamber; a refrigerating coil having a series of traps extending outwardly from said chamber in a closed circuit therewith; one end of said coil connecting to said chamber be-

low the liquid level therein and its other end entering said chamber above the liquid level; a check valve in the coil adapted to restrict flow of the liquid in one direction; a liquid supply pipe connected to said chamber, and means for conducting vaporized refrigerant from said chamber whereby the continuous exhaust of vapor from said chamber will cause spasmodic convulsive ebullition in the lower portion of each succeeding trap of said circuit with intermittent seating and unseating of said valve to cause flow of all alternate slugs of liquid and gas throughout said closed circuit in a continuous flow.

2. An evaporator comprising a refrigerating float chamber; means for maintaining a constant refrigerant level in such chamber; a continuous conduit having a series of traps extending outwardly from said chamber and having an end connected to said chamber below the liquid level therein and having a second end connected to said chamber above the liquid level, movable means to restrict flow of the fluid in one direction through the conduit, and means for conducting vaporized refrigerant from said chamber to effect spasmodic convulsive ebullition of liquid in the conduit with intermittent movement of said restricting means to effect flow of alternate slugs of liquid and gas throughout the conduit in a continuous flow.

3. An evaporator comprising a refrigerating float chamber; means for maintaining a constant refrigerant level in such chamber; a refrigerating coil having a series of traps extending outwardly from said chamber in a closed circuit therewith; one end of said coil connecting to said chamber below the liquid level therein and its other end entering said chamber above the liquid level; a check valve in the coil adapted to restrict flow of the liquid in one direction; a liquid supply pipe connected to said chamber, means for conducting vaporized refrigerant from said chamber whereby the continuous exhaust of vapor from said chamber will cause spasmodic convulsive ebullition in the lower portion of each succeeding convolution of said circuit with intermittent seating and unseating of said valve to cause flow of all alternate slugs of liquid and gas throughout said closed circuit in a continuous flow, and a heat-absorbing fin thereby connected to and disposed within the coil to effect heating of the liquid within certain lower parts of the coil and thereby accelerate ebullition at such points.

4. An evaporator comprising a refrigerating float chamber; means for maintaining a constant refrigerant level in such chamber; a continuous conduit having a series of traps extending outwardly from

said chamber and having an end connected to said chamber below the liquid level therein and having a second end connected to said chamber above the liquid level, movable means to restrict flow of the fluid in one direction through the conduit, and means for conducting vaporized refrigerant from said chamber to effect spasmodic convulsive ebullition of liquid in the conduit 10 with intermittent movement of said restricting means to effect flow of alternate slugs of liquid and gas throughout the conduit in a continuous flow, and heat-absorbing means associated with the conduit to 15 effect heating of the liquid and thereby accelerate ebullition.

5. An evaporator comprising a refrigerating float chamber; means for maintaining a constant refrigerant level in such 20 chamber; a continuous conduit having a series of traps extending outwardly from said chamber and having an end connected to said chamber below the liquid level therein and having a second end connected to 25 said chamber above the liquid level, movable means to restrict flow of the fluid in one direction through the conduit, means for conducting vaporized refrigerant from said chamber to effect spasmodic convulsive 30 ebullition of liquid in the conduit with intermittent movement of said restricting means to effect flow of alternate slugs of liquid and gas throughout the conduit in a continuous flow, and a combined drip collector and heat absorbing means associated 35 with the conduit.

6. An evaporator comprising a refrigerating float chamber; means for maintaining a constant refrigerant level in such 40 chamber; a continuous conduit having a series of traps extending outwardly from said chamber and having an end connected

to said chamber below the liquid level therein and having a second end connected to said chamber above the liquid level, movable 45 means to restrict flow of the fluid in one direction through the conduit, means for conducting vaporized refrigerant from said chamber to effect spasmodic convulsive ebullition of liquid in the conduit with intermittent movement of said restricting means to effect flow of alternate slugs of liquid and gas throughout the conduit in a continuous flow, and a combined drip collector and heat absorbing means thermally 50 connected to the conduit at a plurality of spaced points so as to accentuate convulsive ebullition at such concentrated points.

7. In combination with a refrigerating unit, a refrigerating evaporating duct connected therewith adapted to be freely suspended in a body of air to be cooled, a vertically disposed cuprous heat absorbing plate disposed close and substantially parallel to said duct and in intimate thermal 60 contact with said duct at a plurality of points along its length, whereby the heat absorption property of said duct is increased.

8. In combination with a refrigerating unit, a refrigerant evaporating duct connected therewith and arranged to facilitate a free downward circulation of air past it, a relatively wide and vertically disposed metal heat absorbing fin arranged parallel 75 with and soldered to said duct to accentuate downward convection currents of the surrounding air, the absorption of heat therefrom and to increase evaporation of the refrigerant in the portion of said duct thermally united with said heat absorbing fin.

In testimony whereof I affix my signature.
EDWARD S. HALSEY.
